EXTENSION STUDIO COUCH

Harry Rosen, Cleveland, Ohio

Application November 23, 1937, Serial No. 176,028

3. Claims. (Cl. 5—18)

This invention relates to an extensible couch or bed which is adapted to be used either as a couch or as a bed. The main object of the invention is to provide a combination couch and bed which consists of few parts which are well adapted for quantity production at relatively low cost, and which is so constructed that it may be readily converted into a bed of larger size with a minimum effort.

Another object of the invention is to provide an extension couch which has a back rest or rail which is pivotally mounted on the movable section of the couch and which functions automatically to form a bed of larger size when the back rail is moved forwardly.

A further object of the invention is to provide an extension couch which consists essentially of an upper bed which is movable and a lower stationary bed which is normally disposed under the upper bed and concealed thereby and connected therewith in such a manner that when the back rest is moved to a forward position the two beds are separated so as to provide a bed of larger size.

A still further object of the invention is to provide an extension couch of the character described which has a back rail pivotally mounted on the movable section of the couch and which has arm rests carried thereby, the back rail being so disposed and positioned that when it is moved to a forward position the bed will be readily accessible from either side.

A still further object of the invention is to provide an extensible couch which has a back rail pivotally mounted thereon and which is also provided with mechanism operable only by the swinging movement of the back rail to provide a bed of larger size.

Further and more limited objects of the invention will appear as the description proceeds and by reference to the accompanying drawings in which Fig. 1 is a view in end elevation of my improved couch; Fig. 2 is a view of the couch in its extended position; Fig. 3 is a top plan view of the couch in the position shown in Fig. 1 with the cushions removed; Fig. 4 is a top plan view of the couch shown in Fig. 3 in its extended position; Fig. 5 is a vertical sectional view on the line 5—5 of Fig. 3; and Fig. 6 is a vertical sectional view on the line 6—6 of Fig. 4.

Referring now to the drawings in which one practical embodiment of the invention is disclosed, the reference character 1 designates generally the stationary bed section and the reference character 2 designates the movable bed

section. The stationary bed consists essentially of a rectangular frame member 3 which has secured thereto a suitable spring 4 of usual construction and is also provided with suitable legs 5, 6, 7 and 8. Disposed at the front portion of the stationary bed 3 is an angular member 9 which has an elongated slot 10 therein the purpose of which will hereinafter appear. Also carried by the front portion of the stationary bed 3 is a member 11 which has an upwardly projecting stud 12 thereon the purpose of which will also hereinafter appear.

The movable bed consists of a front frame member 13, end frame members 14 and 15 and a rear frame member 16 which is angular in shape, as shown most clearly in Figs. 5 and 6. Secured to the end frame member 15 in any suitable manner is a member 17 which receives and provides a bearing for a crank 18 which has an arm 19, a straight portion 20 and an arm 21. Secured to the frame members 14 and 15 and projecting upwardly therefrom are a pair of arms 22 and 23. The couch is provided with a back rest 24 which includes a pair of horizontally extending rails 25 and 26 and end members 27 and 28 which form arm rests. The back rails and arm rests are preferably formed of tubular material. Carried by the arm rests 27 and 28 are a pair of members 29 which pivotally engage in the upper end of the arms 22 and 23, the pivots being indicated by the reference character 30. It is to be noted particularly that the arms 22 and 23 are of such a length and the pivots are mounted at such a height that the back rest turns on an axis disposed above the sleeping surface so that when the back rest is moved to the forward position the rail 25 will rest on the floor adjacent the front edge of the bed in the position shown most clearly in Fig. 2.

Carried by the front frame member 13 of the movable bed is an angular member 31 which has therein a slot 32. Also carried by the front frame member 30 is a member 33 which has thereon an upwardly projecting stud 34. The stationary bed and the movable bed are held against separation by means of a pair of toggle arms 35 and 36 which are pivotally connected together centrally thereof by a stud or bolt 37. One end of the arm 35 has a stud 38 thereon which engages in the slot 32 and the opposite end thereof engages over the fixed stud 12. One end of the arm 36 has a stud 39 which engages in the slot 10 and the opposite end thereof engages over the stud 34. The arm 36 has an angular extension 40 thereon the outer end of

which is connected to the arm 21 by means of a link 41. Connected to the arm 19 of the crank 18 is a link 42 the opposite end of which is pivotally connected to the member 29, as shown at 43. The movable bed has four legs 44, 45, 46 and 47 which have casters 48 thereon. The movable bed receives thereon a box spring 49 and disposed over and resting on the box spring 49 is a spring cushion 50. When the couch is moved to the extended position, the spring cushion 50 is moved onto the stationary bed in the position shown in Fig. 1, the box spring 49 remaining on the movable bed. The cushion 50 preferably is slightly narrower than the box spring 49 so as to provide a space at the rear of the couch to receive suitable pillows one of which is shown at 51 in Fig. 1.

When it is desired to form a bed of larger size or to convert the couch into a bed, the back rail 20 is moved from the position shown in Fig. 1 to the position shown in Fig. 2. This movement of the back rail about its pivots causes the arm 19 of the crank 18 to move from the position shown in Fig. 1 to the position shown in Fig. 2 which motion is transmitted through the link 41 to the extension 40 and thence to the toggle arms 35 and 36 to move the movable bed section 2 forwardly automatically. It is to be noted that the movable bed and stationary bed are separated 30 by the mere movement of the back rail from the rearward to the forward position which requires practically no effort on the part of the operator, thus eliminating the necessity for any pulling or lifting.

It will also be noted that the beds cannot be moved apart except by movement of the back rail. This construction also has the advantage of eliminating the possibility or danger that the movable bed may be accidentally pushed forward by a person sitting on the couch, as the movable bed can be moved forwardly only by means of the back rail, the beds being held against separation when the back rail is in the position shown in Fig. 1. When the back rail is 40 in the normal position, it rests against a pair of stops provided on the ends of the movable bed one of which is shown in Fig. 1 and indicated by the reference character 52.

It will now be clear that I have provided an extension couch which will accomplish the objects of the invention as hereinbefore stated. It is of course to be understood that various changes may be made in the details of construction and arrangement of parts without departing from the spirit of my invention and that the embodiment of the invention herein disclosed is to be

considered merely as illustrative and not in a limiting sense as the invention is limited only in accordance with the scope of the appended claims.

Having thus described my invention, what I claim is:

1. An extensible studio couch comprising a stationary bed and an overlying movable bed, means holding said beds against separation, including a back rest pivotally mounted on the 10 movable bed and mechanism connected with said back rest and beds and operable by said back rest to move the movable bed with respect to the stationary bed to provide a larger sleeping surface, said mechanism including a pair of toggle arms connected with said beds respectively, and a crank operable by turning said back rest about its pivots to separate said beds.

2. An extensible studio couch comprising a stationary section and a movable section, a back 20 rest pivotally mounted on the movable section and positioned to turn about an axis disposed in a plane above the sleeping surface whereby the back rest may be moved forwardly and downwardly to a position to give free and unobstructed 25 access to the bed from either side, mechanism connected with said sections operable by turning said back rest about its pivots to separate said sections to form a larger sleeping surface, said mechanism including a pair of toggles connected 30 with said bed sections, and a crank connected with said toggles and back rest and operable by turning movement of said back rest to move said movable section forwardly.

3. In a horizontally extensible couch including 35 an outer bed section and an inner bed section mounted to move rectilinearly relatively to each other into and out of telescoping relation, operative means to move said sections into and out of such telescoping relation comprising equalizing 40 means connecting the two sections operative when actuated to extend the two sections from telescoped relation and to retract the two sections to such relation and means to actuate the equalizing means including a back rest pivotally mounted 45 for swinging movement on said outer section either into a normal back supporting position or into a forward position clear of the top of said outer section and means operatively connecting said back rest with said equalizing means 50 whereby swinging said back rest to forward position extends the sections and swinging said back to back supporting position telescopes the sections.

HARRY ROSEN.
